US00D996422S

(12) **United States Design Patent** (10) **Patent No.:** **US D996,422 S**
(45) **Date of Patent:** **** Aug. 22, 2023**

(54) **ELECTRONIC DEVICE**

(71) Applicant: **Apple Inc.**, Cupertino, CA (US)

(72) Inventors: **Jody Akana**, Los Altos Hills, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Abidur Rahman Chowdhury**, San Francisco, CA (US); **Clara Geneviève Marine Courtaigne**, Palo Alto, CA (US); **Markus Diebel**, San Francisco, CA (US); **Jonathan Gomez Garcia**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Joe Sung-Ho Tan**, Vienna (AT); **Clement Tissandier**, San Francisco, CA (US); **Eugene Antony Whang**, San Francisco, CA (US)

(73) Assignee: **Apple Inc.**, Cupertino, CA (US)

(**) Term: **15 Years**

(21) Appl. No.: **29/852,103**

(22) Filed: **Sep. 2, 2022**

Related U.S. Application Data

(63) Continuation of application No. 29/747,246, filed on Aug. 20, 2020, now Pat. No. Des. 962,930.

(57) **CLAIM**

The ornamental design for an electronic device, as shown and described.

DESCRIPTION

FIG. 1 is a front perspective view of an electronic device showing the claimed design;

FIG. 2 is a rear perspective view thereof;

(Continued)

FIG. 3 is a front view thereof;
 FIG. 4 is a rear view thereof;
 FIG. 5 is a left side view thereof;
 FIG. 6 is a right side view thereof;
 FIG. 7 is a top view thereof; and,
 FIG. 8 is a bottom view thereof.
 The dot-dash broken lines in the figures and the areas outside the dot-dash broken lines show portions of the electronic device that form no part of the claimed design.
